UNITED STATES PATENT OFFICE

JOHN IRVING NASMITH, OF ERITH, ENGLAND, ASSIGNOR TO VICKERS LIMITED, OF WESTMINSTER, ENGLAND, A BRITISH COMPANY

CUTTING AND CREEASING PRESS FOR PAPER, CARDBOARD, OR THE LIKE

Application filed October 2, 1928, Serial No. 309,702, and in Great Britain December 13, 1927.

This invention relates to cutting and creasing presses of the platen type for paper, cardboard or the like, hereinafter referred to as paper. In cutting and creasing machines of the platen type serviceable for use in making folding boxes, a cutting die or forme is built up of steel cutting and creasing rule formed into the required shapes and dimensions of the sheets to be cut and creased, and is suitably supported inside a steel frame known as the chase. The chase and its contents are placed in the machine resting against the plane face provided on the bed of the machine. The machine comprises a platen which is moved relatively to the framework in such a manner that the sheets of paper can be laid on the approximately plane face thereof and be supported thereby as it is carried towards and pressed against the forme. When the platen is moved away from the forme to the open position it enables another sheet of paper to be inserted, but before this can be pressed the impressed sheet adhering to the forme has to be peeled or stripped off and removed. In practice, the machine is run continuously and the operator has to feed the sheets of paper one at a time on to the platen of the machine and also to remove or strip the impressed sheets from the forme and lay them aside. The primary object of the invention is to relieve the operator of all the operations except the feeding of the sheets of paper to the machine, and another object is to enable the machine to be run at a higher speed and a greater output to be obtained than heretofore. The peeling of the sheets of paper from the forme is rendered necessary owing to the fact that the sheets are not free of the steel cutting and creasing rule after they have been pressed against the same by the platen, as the cutting edges of the rule are embedded in the sheets. To effect such peeling each sheet of paper is gripped at one edge for pulling the sheet away from the face of the forme and disengaging it from the embedded cutting edges of the rule. In this respect, therefore, the operation is distinguished from that obtaining in platen printing machine wherein, due to the fact that there is no creasing of the sheet and conse- quently no binding of it to the platen, the sheet does not have to be peeled from the platen but can be withdrawn therefrom in an endwise direction as customary. According to the invention the machine is so constructed that each of the impressed sheets is mechanically or automatically peeled or stripped from the forme or cutting and creasing die and delivered from the machine. For this purpose mechanism is provided which is capable of gripping the impressed sheets and stripping them from the forme, and of effecting their removal during the interval that the platen is opening and closing. This enables the operator to concentrate entirely on feeding the sheets and permits the machine to be run at a higher speed than hitherto without danger to the operator. The mechanism comprises a gripping plate or member which is capable of being disposed behind and of coming to rest against one of the margins of an impressed sheet left projecting beyond the forme, and of co-acting with a number of grippers distributed along its length. The grippers are open when the gripping face is brought into position and comes to rest behind the said margin, but immediately following this the grippers are actuated and moved to the closed position for gripping the margin of the sheet between them and the gripping plate. Means are provided whereby the gripping mechanism is so set in motion as to strip the sheet from the forme, such stripping means being operated immediately after the sheet has been grasped by the grippers and gripping plate. After its detachment from the forme, the sheet is held suspended by the gripping mechanism, and as it is moved back towards the forme the mechanism is actuated and the sheet released therefrom. On release, the sheet is allowed to fall by gravity on to a ledge or plate which serves to position or square it relatively to suitable means for removing it. One such means comprises two spaced ejecting rollers between which the sheet passes in falling on to the ledge or plate. The rollers are timed or arranged to be moved subsequently and engage with the sheet and deliver it on to

a conveyor or delivery band. Following the release of the sheet, the gripping mechanism completes its movement to the initial position, with the grippers in the open position 5 away from the gripping plate. Means are further provided to raise or move the gripping mechanism clear of the platen when this impresses a second sheet on the forme, and after this impression has been made, to lower 10 the mechanism again, the grippers being still in the open position, for engaging the second sheet and effecting the removal thereof as already described in connection with the first sheet of paper.

15 In order that the said invention may be clearly understood and readily carried into effect, the same will now be more fully described by way of example with reference to the accompanying drawings, in which:—

20 Figure 1 is a general side elevation of a creasing machine provided with mechanical means for automatically stripping an impressed sheet from the forme and delivering it from the machine according to the invention.

25 Figure 2 is a part rear elevation of the machine shown in Figure 1.

Figure 3 illustrates to an enlarged scale 30 the gripping mechanism generally, as viewed from the front of the machine, an intermediate part being omitted.

Figure 4 is an elevation of a portion of the part omitted from Figure 3, illustrating the gripping plate and one gripper to a part of 35 the means for actuating the gripper.

Figure 5 is a transverse section taken on the line 5—5 of Figure 4.

Figure 6 shows a side elevation looking 40 in the direction of the arrow 6 in Figure 3 of the mechanism for actuating the grippers and moving them to the closed position for gripping a sheet of paper.

Figure 7 shows a side elevation looking 45 in the direction of the arrow 7 in Figure 3 of the mechanism for moving the grippers to the position for releasing a sheet of paper therefrom.

Figures 8, 9, 10, 11 and 12 are detail views 50 of various relative positions of the gripper releasing mechanism, Figure 10 being a section taken on the line 10—10 of Figure 11, and Figure 11 being a part section taken on the line 11—11 of Figure 10.

The cutting and creasing machine shown 55 in the said drawings, which is provided with the stripping and removal means comprises a machine bed or frame 15 on which is mounted the chase 16 carrying the built up impression forme securely bolted to the plane face 60 17. The machine is driven through the driving shaft 18 provided with fast and loose pulleys 19 and flywheel 20. Geared to the driving shaft 18 is a second shaft 21 carrying two crank discs 22 which form part of 65 the gearing between the two shafts 18 and

21 and are disposed one on each side of the frame. Crank pins 23 are mounted on the discs 22 and through connecting rods 24 actuate the platen 25, on which the sheet to be impressed is placed. The platen is first moved into parallel relationship with the chase 16 and then into close proximity thereto for effecting the impression. The impression sheet remains attached to the forme when the platen is moved to the open position for the introduction of another sheet, and this is repeated at every revolution of the crank pins. The platen is so attached to the connecting rods 24 that the depth of the impression can be varied, and when desired, 70 the impression quickly thrown off entirely. The stripping means comprise two stripping arms 26 mounted on each side of the chase 16 on pivot pins 27 fitted to the framework 15. The primary function of the stripper arms 26 in conjunction with the mechanism connected therewith is to strip the impressed sheet from the forme, and for this purpose the arms have imparted to them a controlled oscillatory angular movement about their pivot pins 75 27. The stripper arms also support between them the aforesaid gripping plate and grippers and during the said motion of the arms the gripping mechanism is opened and closed and engaged with the margin of the sheet of 80 paper and operated for releasing the same after detachment of the sheet from the forme. The gripping mechanism comprises a gripper bar 29 which is carried by brackets 28 capable of sliding movement lengthwise of the stripper arms 26, the latter being formed at their upper ends with channels or slide-ways 28a (see Figures 3, 6 and 7) for the engagement therewith of the brackets 28. The lowest position to which the gripper bar 29 85 may be moved is regulated by adjustable stops 30. The stripper arms 26 have springs 31 attached thereto for compensating inertia effects and to steady the motion of the said arms. The two stripper arms 26 are connected together by a tie bar 32 and are actuated from the crank shaft 21 through the 90 medium of cams 33, and rollers 34a on the lower extremities 34b of levers 34 pivoted near their lower ends on pins 35 mounted in brackets 36 on the framework 15. The levers 34 are connected at their upper ends by links 37 to the arms 26 while the rollers 34a engage with the cams 33. The rotation of the cams 33 thus oscillates the levers 34 and a similar motion is imparted to the arms 26 through the connecting links 37. It will be understood 95 that all the parts referred to in this section are duplicated on the other side of the machine with the exception of the tie-bar 32. The cams 33 which actuate the levers 34 also serve to actuate levers 38 pivoted on pins 39 on brackets 40 attached to the framework 15, the levers 38 serving to operate blocks 42 with which blocks 44 on the brackets 28

engage during a part of the movement of the arms 26. The lever 38 includes an extension 38^a carrying a roller 38^b which engages the cam 33, such engagement causing the actuation of the lever 38 during the rotation of the cam. During the time that the stripper arms 26 are stationary and in close proximity to the frame 15, the gripper bar 29 is raised and lowered for manipulating the impressed sheet of paper. To effect this movement of the gripper bar 29 each side of the frame 15 contiguous to the plane face 17 is provided with grooves 41 parallel with the face 17 and in such grooves are disposed the blocks 42 which slide in the grooves and are actuated from the cams 33 through the said levers 38 and links 43, the latter connecting the sliding blocks 42 with the levers 38. The actuation of the levers 38 by the cams 33 impart an intermittent reciprocating motion to the blocks 42, and such motion is transmitted to the gripping bar 29 when the projecting blocks 44 on the brackets 28 impinge against or engage with and are disposed in the path of the slidable blocks 42 during the part of each oscillatory movement of the stripper arms 26 when the stripper arms 26 are close to the frame 15. To avoid inertia stresses, cushioning springs 45 as shown in Figures 6 and 7 are disposed in the slidable blocks 42. The extent of reciprocating motion of the slidable blocks is sufficient to accommodate the range of setting of the adjustable stops 30 for the gripper bar 29. So far as the interaction in sequence of the blocks 44 on the brackets 28 and the slidable blocks 42 is concerned, in the position shown in Figure 1, the grippers have just released an impressed sheet previously stripped from the forme, and the stripper arms 26 are moving in the direction of the arrow 46 and the platen 25 with another sheet laid on it, is travelling towards the forme 16. When the stripper arms 26 occupy a position such that the gripper bar 29 is capable of sliding parallel to the front of the forme and at the correct distance from it, as shown in Figure 7, they become stationary, and in this position the blocks 44 on the gripper bar carrying brackets 28 are over the slidable blocks 42 which are now moved upwards by the cams 33 and levers 38 and raise the brackets 28 and the gripper bar 29 clear for the platen to pass thereunder and press the sheet on the forme. Following this, the platen returns, that is, it is moved away from the forme, and leaves the impressed sheet attached thereto. The slide blocks 42 are then lowered and permit the gripper bar 29 to move into position for the grippers 47 in conjunction with the gripping plate 48 as shown in Figures 4 and 5, to grasp the upper projecting portion of the impressed sheet after the cessation of downward movement of the gripper bar 29. The position to which the gripper bar is allowed to move downwardly or come to rest is regulated by the adjustable stops 30. The gripper bar 29 is thus supported on the adjustable stops 30 in a stationary condition, and the stripper arms 26 commence to move away from the forme with the grippers in action gradually drawing the impressed sheet off the forme. When this is completed the stripper arms 26 commence to return and the grippers are concurrently moved for releasing the impressed sheet of paper, after which the stripper arms 26 return to the position shown in Figure 1. The grippers 47 are moved to the closed position through a notched bar 49 and the mechanism for operating the bar and grippers is more particularly shown in Figures 3, 4 and 5 and is provided on the side of the stripping mechanism shown in Figure 6, that is on the opposite side to that shown in Figure 1, while the mechanism for operating the gripping means to the release position is shown in Figures 1 and 7 to 12 inclusive. A plurality of grippers are employed, two of which are disposed on the gripper bar 29 at the points indicated by the lines 50 in Figure 3. After the stripped impressed sheet has been released by the grippers 47 it falls by gravity and its lower edge engages with and is guided by the guides or inclined walls 51 between delivery rollers 52 on to the conveyor belt 53. The rollers 52 are revolved continuously but are not capable of making contact with and gripping the sheet at the time it falls and therefore, under these conditions they do not assist in transmitting the sheet forward until after its lower edge has fallen on to and makes contact with the conveyor belt 53. In falling on to the conveyor belt 53 the impressed sheet is caused to move to a position in which its lower edge is parallel with the face of the belt and thus the sheet is squared before ejection through the frame of the machine. The delivery rollers 52 are rotated through gearing 54 and a belt 55 connected with the main shaft 18, and one of the delivery rollers 52 is capable of being moved through a lever 56 about the spindle 57 of part of the gearing 54, towards and away from the other delivery roller the movement of the one roller into close proximity to the other roller serving to engage the impressed sheet with the delivery rollers for effecting the removal thereof in a squared condition. The movement of one delivery roller towards and away from the other delivery roller is effected by connecting the upper extremity of the lever 56 by a link 58 to double arm lever 59 which is pivoted on a pin 60 on the framework of the machine and has its upper end fitted with a roller 59^a held in contact with the outer surface of the cam 33 by springs not shown in the drawings. The outer surfaces of the cam 33 is so shaped that immediately after the impressed sheet has been released by the grippers and fallen on to the conveyor 53, 130

the lever 56 is actuated to move one of the delivery rollers towards the other roller for gripping the impressed sheet between them and propelling it on the conveyor 53 which serves to pass the sheet on to the conveyor 61 which finally carries the sheet clear of the machine into a suitable receptacle placed at the rear thereof. The continued rotation of the cam 33 permits a return movement of the lever 56 and the movement of one of the delivery rollers away from the other roller to enable a succeeding impressed sheet to fall between the rollers and to be squared off and then delivered from the machine. The foregoing description sets forth the operation of the mechanism for stripping and delivering the impressed sheets of paper and it is now proposed to describe in detail the construction of the parts already mentioned. As regards the gripper mechanism which comprises the gripper bar 29, grippers 47, gripping plate 48 and notched bar 49, reference is directed more particularly to Figures 3, 4 and 5, wherein z in Figure 5 designates the sheet after it has been impressed on the forme. The gripper bar 29 shown in section in this view and in the position it will occupy relative to the sheet z when the brackets 28 have fallen on to the adjustable stops 30, has attached to it the back or gripping plate 48 which is secured to the said brackets 28. Secured to the gripping plate 48 at suitable intervals along its length are blocks 63 which carry pivot pins 64 for the grippers 47 and these are connected through pins 65 to spring controlled plungers 66. Passing through guide slots 67 formed in the blocks 63 is the notched bar 49 which extends from one side of the machine to the other and is controlled as hereinafter described. This bar 49 is provided with a number of inclines 68, as shown in Figure 4, so disposed as to operate in conjunction with the plungers 66 which are slotted out as previously mentioned for the bar 49 to pass through and are formed with inclines 69 which co-act with the inclines 68 of the notched bar 49 as will be clear from Figure 4. The springs 72 controlling the plungers 66 maintain the inclines 68 and 69 in sliding contact, while the movement of the bar 49 lengthwise regulates the position of the spring controlled plungers 66 and the opening and closing of the grippers 47. As shown in Figures 4 and 5 the grippers 47 are in the open position and permit the upper edge of the impressed sheet to be received into the space left between the gripper plate 48 and the grippers 47. To facilitate the reception of the said upper edge of the impressed sheet, the said gripping plate is chamfered as at 70. To operate the grippers 47 for gripping the edge of an impressed sheet between them and the gripping plate 48, the notched bar 49 is moved in the direction of the arrow 71, shown in Figure 4 for moving the inclines 68 on the bar 49 away from the inclines 69 on the plungers 66 and permit the latter to be raised by the springs 72. Such movement actuates the grippers 47 through the connecting pins 65 and pivot pins 64 and causes them to grip the edge of the impressed sheet against the gripping plate 48. When the notched bar 49 is operated in the reverse direction, the inclines 68 will bear against the inclines 69 on the plungers 66 and pull the plungers down in opposition to the pressure of the springs 72 and the grippers 47 will be moved to the open position, and the edge of the sheet released. From this it will be understood that if the notched bar 49 is actuated from side to side across the machine at the correct times, the sheets will be gripped and released in the requisite order. The means for operating the notched bar 49 for moving the grippers to the closed position for gripping the sheet, that is by moving the notched bar 49 in the direction of the arrow 71, are shown in Figures 3 and 6. In these figures the gripper bar bracket 28 carries a pivot pin 73 on which is movably supported a double arm lever 74. One arm of this lever engages at 75 with the end of the notched bar 49 and the other arm is provided with a projection 76 which engages a recess 77 cut into the top of the notched bar 49. This recess 77 and projection 76 guard against right to left movement of the bar 49 under the influence of the inclines 68 and 69 and the springs 72. The double arm lever 74 is also formed with an extension 78 which engages as required with a pawl 79 pivoted on a pin 80 carried on an extension 81 of the slide block 42. The pawl 79 is held normally in the position shown in Figure 3 by a spring 82 against the stop formed on the extension of the slide block 42 carrying the pivot pin 80. As viewed in Figure 3 the pawl 79 cannot therefore move on its pivot pin 80 in a clockwise direction but is controlled in the other direction only by the spring 82. In the position shown in Figure 3 the carrier bracket 28 and the gripper bar 29 are supported on the adjustable stops 30 provided on the stripper arms 26, but the downward motion of the slide blocks continues and consequently the pawl 79 continues its downward motion while it will be understood that the double arm actuating lever 74 is at rest. In the position shown in Figure 3, contact between the pawl 79 and the lever 74 has just been established and as the pawl 79 is immovable as regards clockwise rotation, the further downward movement of the slide block 42 carrying with it the pawl 79 actuates the double arm lever 74 and turns it in a clockwise direction and disengages the projection 76 thereon from the recess 77 in the bar 49. Upon this movement of the lever 74, not only does the projection 76 release the notched bar 49 but the arm which engages at 75 with the end of the bar 49

moves it lengthwise from right to left in the direction of the arrow 71 (Figure 4) and moves the grippers 47 to the closed position. When the pawl 79 has passed the double arm lever 74 this is returned by its control spring 82 and comes to rest with the projection 76 bearing on the plain upper surface of the notched bar 49. Upon the notched bar 49 being moved in the opposite direction to that indicated by the arrow 71, (Figure 4) the projection 76 again engages the recess 77 and holds the bar against movement until the double arm lever 74 is again actuated as described. After the grippers have thus been operated by the movement of the bar 49 in the direction of the arrow 71 to engage the sheet, the stripper arms 26 perform their angular movement during which the notched bar 49 is operated in the reverse direction to move the grippers 47 to the open position for releasing the impressed sheet and permitting it to fall between the rollers 52 as previously described. The stripper arms 26 then move towards the forme and the slide blocks 42 return to pick up the gripper bar 29 through the brackets 28 and lift it out of the way of the platen for the next closure of the platen faces. During the return of the slide blocks 42 the pawl 79 on the block shown in Figure 6 again engages the projection on the double arm lever 74 but in a reverse direction, and as the mass of the gripper bar is considerable and the pawl 79 is only controlled against counterclockwise rotation by the slight spring 83, the pawl 79 clicks past the projection on the double arm lever 74 and the spring returns the pawl 79 to its stop position ready to positively engage the double arm lever 74 again on the next downward travel of the slide blocks 42. The mechanism for actuating the notched bar 49 in the reverse direction to that indicated by the arrow 71 (Figure 4), for moving the grippers 47 to the open position is more particularly shown in Figures 3 and 7 to 12 inclusive, Figures 3 and 7 showing the gripper bar 29 and stripper arms 26 in the position close to the forme and Figures 8 to 12 inclusive showing this portion of the mechanism separate from the rest of the stripping mechanism. Rigidly secured to the stop 30 on the arm 26 shown on the left hand side of Figure 3, and in Figures 8 and 9, is a member 83 formed with a guide-way 84 in which is adapted to slide a block 85 carrying a pivot pin 86. On this pivot pin is mounted a block 87 provided with a pivot pin 88 on which is mounted a detent 89 normally held in a vertical position by a spring 90 through the medium of the pins 91 and 92 secured in the block 87 and detent 89 respectively. The block 87 also carries a pin 93 to which is connected a link 94 adjustable in length through the medium of its remaining parts 95 (see Figure 1) and 96 and 97 (Figures 8 and 9) to suit the position in which the stop 30 is set, the lower end of the link connection being made to a pivot pin 98 as shown in Figure 1. By the relative arrangement and disposition of the pivot pin 27 of the stripper arms 26 and the pivot pin 98 of the adjustable link 94 and parts 95 and 96 connected therewith it will be apparent that as the stripper arms 26 swing to and fro about their common pivotal centre relative motion will take place between the member 83 and block 87. So far as sliding motion is concerned, relative motion of these two parts 83 and 87 is such that the block 87 is in its lower position when the stripper arms 26 are in the position shown in Figure 7, and in its highest relative position when the stripper arms 26 are at the other extremity of their angular motion. It will be understood from the foregoing that during the whole of the to and fro angular motion of the stripper arms 26, the gripper bar brackets 28 are resting on the stops 30. Supposing now the grippers 47 to be in the closed position suitable for grasping an impressed sheet the disposition of the parts of the release mechanism at this time is shown in the left hand side of Figure 3 and in Figure 7. With the parts thus disposed, the stripper arms 26 carrying the gripper bar 29 and all its mechanism through the brackets 28 swing away from the forme, the slide block 87 carrying with it the detent 89 rises relatively to the gripper bar 29 and all parts connected thereto and the detent 89 which is held clear of a projection 100 on the end of the slide bar 101 is moved upwards relatively to the projection 100 which slide bar engages with one arm of a double arm lever 102 the other arm of which engages with the opposite end of the notched bar 49 to that engaged by the double arm lever 74. From an inspection of Figures 9, 11 and 12 it will be seen that the part of the detent 89 which is capable of being engaged with and disengaged from the projection 100 is the projecting part 99. When the stripper arms 26 are at their extreme position away from the forme relative motion of the said parts ceases and the position of the parts is as shown in Figures 7, 8 and 9 the detent 89 due to the limited dimension of the projecting part 99 being now in a position such that it engages with the projection 100 on the slide bar 101 when moved downwards. As the stripper arms 26 return towards the forme the relative motion is reversed and the pivot block 87 carrying the detent 89 falls relatively to the gripper bar 29 with the projecting part 99 of the detent 89 engaged with the projection 100 of the slide bar 101 and consequently the latter is drawn downwardly in relation to the gripper bar 29 and the grippers 47 are moved to the open position. When this has taken place the pivot block 87 when rotation is possible swings to its limiting position, as shown in Figure 12, before

again beginning to slide. The projecting part 99 on the detent 89 is thus drawn clear of the projection 100 of the slide bar 101. A pin 104 on the pivot block 87 makes contact with the projecting portion of the block 83 and restores positively the pivot block 87 to the relative angular position in which sliding will again take place on the reversal of the motion, the relative position of the parts being now again as in Figures 3 and 7. The fixed member or block 83 is formed with a recessed portion designated 105 in Figure 11 and adapted to engage as required with the pin 104. The pivot block 87 has a projection designated 106 in Figure 9 adapted to engage the side of the fixed block 83, the lower wall of which is terminated by a face 107 which is radial from the pivot pin 86. The upper part of the projection 106 is curved and extends to one side beyond the side wall 108 of the projecting part 109 on the pivot block 87. As long as the projection 106 is in engagement with the side of the fixed block 83 only sliding motion is possible for the pivoted block 87 and it cannot rotate about the pivot pin 86. As soon as the upper edge of the projection 106 arrives at the radial termination 107 of the lower wall of the fixed block 83 in the relative movement of these parts, partial rotation of the pivoted block 87 is possible, and will take place owing to the disposition of the pivotal centre 86. Figures 11 and 12 show these details more clearly and in two positions. Again referring to the left hand side of Figure 3 and to Figure 7, the left hand carrier for the gripper bar 29 carries a pin 110 on which pivots the doubled arm operating lever 102, one arm of which, as previously mentioned, engages the left hand end of the notched bar 49 in a similar manner to that which the operating lever 74 engages the other end, while the other arm of the operating lever 102 engages in a slot in the slide bar 101 which slides in a slot in the carrier bracket 28 of the gripper bar 29. When the notched bar 49 is moved from right to left in the direction of the arrow 71 from the other side of the machine as already described, the double arm lever 102 lifts up the slide bar 101 and as the gripper springs 72 are acting in such a manner through the inclines 68 and 69 as to resist any movement of the notched bar 49 in the opposite direction from left to right, the parts remain in the position in which they are left by the action of the operating lever 74 at the right hand side of the machine. Thus the projecting portion 100 of the slide bar 101 will be in its highest position when this has taken place and if it is pulled downwards it will, through the operating lever 102 push the notched bar 49 from left to right in opposition to the action of the gripper springs 72 through the inclines 68 and 69 and move the grippers 47 to the open position. In thus moving the notched bar 49 in the opposite di-

rection to that indicated by the arrow 71 the catch 76 will again fall into the recess 77 in the top of the notched bar 49 and hold it in this position until it is again operated. It will be clear from the above that the slide bar 101 only requires to be pulled down at the desired time to move the grippers to the open position, the position of the slide bar 101 being restored by the mechanism shown in Figure 6 and on the right hand side of Figure 3 as already described. 70 75

The mechanism for mechanically and automatically stripping the impressed sheets from the forme as hereinbefore described may be used in connection with cutting and creasing and similar machines no matter whether the sheets are fed by hand or by mechanical means. 80

What I claim and desire to secure by Letters Patent of the United States is:— 85

1. A cutting and creasing press for paper comprising, an impression forme, means enabling paper to be introduced into the press, means for pressing the forme and the paper together, and means operating with a peeling action for removing the paper from the forme. 90

2. A cutting and creasing press for paper comprising, an impression forme, means enabling paper to be introduced into the press, means for pressing the forme and the paper together, means operating with a peeling action for removing the paper from the forme, and means for delivering from the press the paper from the forme. 95 100

3. A cutting and creasing press for paper comprising, an impression forme, means enabling individual sheets of paper to be fed to the forme, means for pressing the forme and the individual sheets of paper together, and means operating with a peeling action for removing the individual sheets of paper from the forme. 105

4. A cutting and creasing press for paper comprising, an impression forme, means enabling individual sheets of paper to be fed to the forme, means for pressing the forme and the individual sheets of paper together, means operating with a peeling action for removing the individual sheets of paper from the forme, and means for delivering from the press the sheets of paper peeled from the forme. 110 115

5. A cutting and creasing press for paper comprising, an impression forme, means enabling individual sheets of paper to be fed to the forme, means for pressing the forme on to the individual sheets of paper, mechanically operated gripping devices engageable with the margins of the individual sheets of paper, means for moving the grippers away from the forme and removing the sheets therefrom with a peeling action, and means for delivering the sheets from the press. 120 125 130

6. A cutting and creasing press for paper comprising an impression forme, means enabling individual sheets of paper to be fed to the forme, means for pressing the forme on to the paper, mechanically operated gripping devices, means for lowering the devices to the margins of the sheets, means for engaging the devices with the said margins, means for moving the devices away from the forme and peeling the individual sheets of paper therefrom, and means for releasing the sheets from the device and delivering them from the press.

7. A cutting and creasing press for paper comprising, an impression forme, means enabling individual sheets of paper to be fed to the forme, means for pressing the individual sheets of paper on to the forme, mechanically operated gripping devices, means for engaging the devices with the margins of the sheets, means for moving the devices away from the forme and peeling the sheets from the forme, means for releasing the individual sheets from the grippers, a sheet squaring member, means directing the sheets on to and arranging them parallel with the squaring member, and means for delivering the squared sheets from the press.

8. A cutting and creasing press for paper comprising, an impression forme, means enabling individual sheets of paper to be fed to the forme, a pair of rotatable discs on the same axle, mechanism actuated by the discs for pressing the forme and the sheets of paper together, cams on the discs, gripping devices capable of engaging the individual sheets of paper on the forme, mechanism carrying the devices for peeling the individual sheets from the forme, members on the mechanism carrying the devices and engaging the cams, and means for delivering the sheets of paper from the press.

9. A cutting and creasing press for paper comprising, an impression forme, means for enabling individual sheets of paper to be fed to the forme, a pair of rotatable discs on the same axle, mechanism actuated by the discs for pressing the forme and the sheets of paper together, cams on the discs, gripping devices capable of engaging the individual sheets of paper on the forme, mechanism carrying the devices for peeling the individual sheets from the forme, members on the mechanism carrying the devices and engaging the cams, and means for delivering from the press the sheets of paper peeled from the forme.

10. A cutting and creasing press for paper comprising an impression forme, means enabling individual sheets of paper to be fed to the forme, a pair of rotatable discs on the same axle, mechanism actuated by the discs for pressing the forme and the sheets of paper together, cams on the discs, gripping devices capable of engaging the individual

sheets of paper on the forme, mechanism carrying the devices for peeling the individual sheets from the forme, members on the mechanism carrying the devices and engaging the cams, and means for releasing the sheets from the devices and delivering them from the press.

11. A cutting and creasing press for paper comprising, an impression forme, means enabling individual sheets of paper to be fed to the forme, a pair of rotatable discs on the same axle, mechanism actuated by the discs for pressing the forme and the sheets of paper together, cams on the discs, gripping devices capable of engaging the individual sheets of paper on the forme, mechanism carrying the devices for peeling the individual sheets from the forme, members on the mechanism carrying the devices, and engaging the cams, means for releasing the individual sheets from the devices, a sheet squaring member, means directing the sheets on to and arranging them parallel with the squaring member, and means for delivering the squared sheets from the press.

12. A cutting and creasing press for paper comprising, an impression forme, means enabling paper to be introduced into the press, a pair of rotatable discs on the same axle, mechanism actuated by the discs for pressing the forme and the sheets of paper together, cams on the discs, gripping devices capable of engaging the individual sheets of paper on the forme, mechanism carrying the devices for peeling the individual sheets from the forme, members on the mechanism carrying the devices and engaging the cams, means for releasing the sheets from the devices, guides for the passage of the released sheets, and means for delivering the sheets of paper from the press.

13. A cutting and creasing press for paper comprising, an impression forme, means enabling paper to be introduced into the press, a pair of rotatable discs on the same axle, mechanism actuated by the discs for pressing the forme and the sheets of paper together, cams on the discs, gripping devices capable of engaging the individual sheets of paper on the forme, mechanism carrying the devices for peeling the individual sheets from the forme, members on the mechanism carrying the devices and engaging the cams, means for releasing the sheets from the devices, guides for the passage of the sheets, intermittently operated rollers for removing the sheets from the guides, and means for delivering the sheets of paper from the press.

14. A cutting and creasing press for paper comprising, an impression forme, means enabling individual sheets of paper to be fed to the forme, a pair of rotatable discs on the same axle, mechanism actuated by the discs for pressing the forme and the sheets of paper together, cams on the discs, gripping de-

- vices capable of engaging the individual sheets of paper on the forme, mechanism carrying the devices for peeling the individual sheets from the forme, members on the mechanism carrying the devices and engaging the cams, means for releasing the sheets from the devices, guides for the passage of the sheets, intermittently operated rollers for removing the sheets from the guides, mechanism operated by the cams on the discs for moving one of the rollers relatively to the other intermittently operated roller, and means for delivering the sheets of paper from the press.
15. A cutting and creasing press for paper comprising, an impression forme, means for enabling individual sheets of paper to be fed to the forme, a pair of rotatable discs on the same axle, mechanism actuated by the discs for pressing the forme and the sheets of paper together, cams on the discs, gripping devices capable of engaging the individual sheets of paper on the forme, mechanism carrying the devices for peeling the individual sheets from the forme, members on the mechanism carrying the devices and engaging the cams, means for releasing the sheets from the devices, guides for the passage of the released sheets, intermittently operated rollers for removing the sheets from the guides, and a conveyor which receives the sheets from the rollers and delivers the sheets from the press.
16. A cutting and creasing press for paper comprising, an impression forme, means enabling individual sheets of paper to be fed to the forme, a pair of rotatable discs on the same axle, mechanism actuated by the discs for pressing the forme and the sheets of paper together, cams on the discs, gripping devices capable of engaging the individual sheets of paper on the forme, mechanism carrying the devices for peeling the individual sheets from the forme, members on the mechanism carrying the devices and engaging the cams, means for releasing the sheets from the devices, guides for the passage of the sheets, a pair of intermittently operated rollers for removing the sheets from the guides, mechanism operated by the cams on the discs for moving one of the rollers relatively to the other roller, and a conveyor for receiving the sheets from the rollers and delivering them from the press.
17. A cutting and creasing press for paper comprising, an impression forme, means enabling individual sheets of paper to be fed to the forme, means for pressing the individual sheets of paper on to the forme, a pair of rotatable discs on the same axle, mechanism actuated by the discs for pressing the forme and the sheets of paper together, cams on the discs, gripping devices capable of engaging the individual sheets of paper on the forme, mechanism carrying the devices for peeling the individual sheets from the forme,

members on the mechanism and engaging the cams and means for delivering the sheets of paper from the press, means for releasing the individual sheets from the devices, a sheet squaring member, guides directing the sheets on to and arranging them parallel with the squaring member, intermittently operated rollers for removing the squared sheets and a conveyor which receives the sheets from the rollers and delivers them from the press.

18. A cutting and creasing press for paper comprising, an impression forme, means enabling paper to be introduced into the press, a pair of rotatable discs on the same axle, mechanism actuated by the discs for pressing the forme and the sheets of paper together, cams on the discs, gripping devices capable of engaging the individual sheets of paper on the forme, an oscillatable frame carrying the devices for peeling the individual sheets from the forme, members on the frame and engaging the cams, and means for delivering the sheets of paper from the press.

19. A cutting and creasing press for paper comprising, an impression forme, means enabling paper to be introduced into the press, a pair of rotatable discs on the same axle, mechanism actuated by the discs for pressing the forme and the sheets of paper together, cams on the discs, spring controlled gripping devices capable of engaging the individual sheets of paper on the forme, an oscillatable frame carrying the devices for peeling the individual sheets from the forme, members on the frame and engaging the cams, means on one side of the frame for closing the gripping devices, means on the opposite side of the frame for opening the devices, and means for delivering the sheets of paper from the press.

20. A cutting and creasing press for paper comprising, an impression forme, means enabling individual sheets of paper to be fed to the forme, a pair of rotatable discs on the same axle, mechanism actuated by the discs for pressing the forme and the sheets of paper together, cams on the discs, spring controlled gripping devices capable of engaging the individual sheets of paper on the forme, an oscillatable frame carrying the devices for peeling the individual sheets from the forme, members on the frame and engaging the cams, means on one side of the frame for closing the gripping devices, means on the opposite side of the said frame for opening the devices, means actuated by the cams for moving the devices on the frame, and means for delivering the sheets of paper from the press.

21. A cutting and creasing press for paper comprising, an impression forme, means for enabling individual sheets of paper to be

- fed to the forme, a pair of rotatable discs on the same axle, mechanism actuated by the discs for pressing the forme and the sheets of paper together, cams on the discs, spring controlled gripping devices capable of engaging the individual sheets of paper on the forme, an oscillatable frame carrying the devices for peeling the individual sheets from the forme, members on the frame and engaging the cams, means on one side of the frame for closing the gripping devices, means on the opposite side of the frame for opening the devices, means actuated by the cams for moving the devices on the frame, guides for the passage of released sheets of paper and means for delivering from the press the sheets of paper peeled from the forme and released from the devices. 70
22. A cutting and creasing press for paper comprising, an impression forme, means enabling individual sheets of paper to be fed to the forme, a pair of rotatable discs on the same axle, mechanism actuated by the discs for pressing the forme and the sheets of paper together, cams on the discs, spring controlled gripping devices capable of engaging the individual sheets of paper on the forme, an oscillatable frame carrying the devices for peeling the individual sheets from the forme, members on the frame and engaging the cams, means on the frame for closing and opening the devices, means actuated by the cams for moving the devices on the frame, guides for the passage of the released sheets of paper and means for delivering from the press the sheets of paper peeled from the forme and released from the devices. 75
23. A cutting and creasing press for paper comprising an impression forme, means enabling individual sheets of paper to be fed to the forme, a pair of rotatable discs on the same axle, mechanism actuated by the discs for pressing the forme and the sheets of paper together, cams on the discs, springs controlled gripping devices capable of engaging the individual sheets of paper on the forme, an oscillatable frame carrying the devices for peeling the individual sheets from the forme, members on the frame and engaging the cams, means for closing and opening the devices, means actuated by the cams for moving the devices on the frame, guides for the passage of the released sheets, intermittently operated rollers for removing the sheets from the guide, and means for delivering the sheets from the press. 80
24. A cutting and creasing press for paper comprising, an impression forme, means enabling individual sheets of paper to be fed to the forme, a pair of rotatable discs on the same axle, mechanism actuated by the discs for pressing the forme and the sheets of paper together, cams on the discs, spring controlled gripping devices capable of engaging the individual sheets of paper on the forme, an oscillatable frame carrying the devices for peeling the individual sheets from the forme, members on the frame and engaging the cams, means for closing and opening the devices, means actuated by the cams for moving the devices on the frame, guides for the passage of the released sheets, intermittently operated rollers for removing the sheets from the guides, mechanism operated by the cams on the discs for moving one of the rollers relatively to the other roller, and a conveyor which receives the sheets from the rollers and delivers them from the press. 85
25. A method of stripping impressed sheets of paper from the forme of a cutting and creasing press, consisting in gripping one of the margins of each individual sheet of paper, moving the gripped margins of the successive sheets individually transversely away from the forme to peel the respective sheets therefrom the separation of the respective sheets from the forme commencing at one edge thereof and gradually extending across to the opposite edge, releasing the margins of the successive sheets and delivering the released sheets from the press. 90
26. A method as in claim 25, further consisting in squaring each individual sheet to lie in a predetermined direction after being released and before being delivered from the press. 95
27. A mechanism for stripping impressed sheets from the forme of a cutting and creasing press comprising a movable frame carrying sheet gripping devices, means for mounting the mechanism on the press, means for moving the frame towards the forme, means for closing the gripping devices on the margin of the sheet, means for moving the frame from the forme and peeling the impressed sheet therefrom, means for releasing the impressed sheet from the devices, means for guiding the passage of the released sheet, means for squaring the edge of the released sheet and means for delivering the sheet from the squaring means. 100
